Attorney.

UNITED STATES PATENT OFFICE

2,446,452

HAND SLED

Merle K. Benson, Benton Harbor, Mich., assignor
to T-M-K Corporation, Davenport, Iowa, a cor-
poration of Iowa

Application October 3, 1946, Serial No. 701,016

10 Claims. (Cl. 280—22)

1

This invention relates to improvements in hand sleds.

The main objects of this invention are:

First, to provide a hand sled which is formed of metal including a top or deck and at the same time of moderate weight.

Second, to provide a hand sled in which the raves, runners, and struts are formed of a single piece of tubing or rod stock.

Third, to provide a hand sled having these advantages which may be economically produced.

Further objects relating to details and economies of the invention will appear from the description to follow. The invention is defined in the claims.

A structure which embodies the features of the invention is illustrated in the accompanying drawing, in which:

Fig. 1 is a plan view of a hand sled embodying my invention.

Fig. 2 is a side elevational view thereof.

Fig. 3 is a perspective view of the structure with the deck or top and steering mechanism removed.

Fig. 4 is an enlarged fragmentary view in vertical section on a line corresponding to line 4—4 of Figs. 1 and 2.

Fig. 5 is an enlarged fragmentary view in longitudinal section on a line corresponding to line 5—5 of Fig. 1.

Fig. 6 is an enlarged fragmentary view showing details of the steering mechanism on a line corresponding to line 6—6 of Fig. 1.

Fig. 7 is an enlarged fragmentary view of a modified form or embodiment of my invention, the section corresponding to line 7—7 of Fig. 6.

In the preferred embodiment of my invention illustrated in Figs. 1 to 6 inclusive the raves 1, runners 2, and strut members 3 are formed of a single piece of tubing bent to provide these several parts. The raves are connected at their front ends by the forwardly bowed cross piece 4. The rear ends of the raves are turned downwardly at 5 to merge at 6 with the runners 2. The front ends of the runners are directed upwardly at 7 and the stock is thence bent rearwardly into V-shaped strut members 3 which engage the top of the runners centrally thereof at 8 and are welded thereto as indicated at 9, Fig. 4. The rear arms 10 of the strut members are welded to the under side of the raves at 11.

The cross bar 12 also formed of a piece of tubing in this preferred embodiment stands between the forward ends of the forward arms 14 of the

2

strut members and is welded at 15 to the inner sides thereof. The welds are not illustrated, as they will be understood.

The deck or top 16 is formed of a sheet metal plate or panel having its side edges 17 raised around the raves 1 and welded thereto as indicated at 18. The front end of the deck or top is curved downwardly at 19 to overhang the cross piece 4, connecting the front ends of the raves and is welded thereto as indicated at 20. The rear edge of the deck is rounded and downwardly curved as shown at 21. The deck thus supported and secured in association with the raves serves the function of benches and thus results in economy of material and also in minimizing weight. The deck, being welded to the raves front cross piece is strongly supported even when formed of relatively light sheet stock.

The steering arm or member 22 is in the form of a dished segmental plate and is pivotally mounted at 23 on the cross bar 12. The rear end of the arm or steering plate is pivotally connected by the pivot bolt 24 to the forwardly projecting bracket 25, centrally positioned on the cross piece 4. The upwardly flaring portion 26 of the steering plate is provided with a down-turned rim 27 receiving the curved steering bar 28 which is welded thereto as indicated at 29. The handle bar projects beyond the steering plate and is provided with suitable non-metallic grips 30. The steering plate or plate-like steering arm thus provides a rounded front surface which is not likely to injure a child or object which the sled may contact, and the handle or steering bar is supported so that it may be formed of comparatively light stock and at the same time strong and rigid.

The knees 31 are formed of straight pieces of tubing or rod, their upper ends being welded to the under sides of the raves and their lower ends rested upon and being welded to the strut members at their point of attachment to the runners. The strut arms 10 are in effect combination braces or struts and knees.

With the parts thus arranged, an all metal structure is provided, without excessive weight and at the same time it is very strong and durable.

In the embodiment shown in Fig. 7, the raves, runners, and strut members are formed of two pieces of stock 32, joined at their ends in the rave cross piece 41 corresponding to the cross piece 4 by means of the coupling sleeve 33, carrying the bracket 34 to which the steering plate 22 is connected. The sleeve 33 is arranged between the ends of the members 32 and parts are

welded at 36 and 37 making in effect an integral structure, however, one which has somewhat less complications in the matter of bending the stock to form the several unitary parts.

I have illustrated and described my invention as embodied in a structure which I consider very desirable commercially. I have not attempted to illustrate or describe other embodiments or adaptations, as it is believed that this disclosure will enable those skilled in the art to embody or adapt my invention as may be desired.

Having thus described my invention, what I claim as new and desire to secure by Letters Patent is:

1. A sled comprising raves and runners and V-shaped strut members formed integrally of a piece of tubular stock, the raves being connected at their front ends by an integral forwardly bowed rave cross piece, the rear ends of the raves being curved downwardly and merging with the rear ends of the runners, the front ends of the runners being curved upwardly and extended rearwardly into the V-shape strut members, the bights of which are welded to the upper sides of the runners, the rear arms of the strut members being welded to the under sides of the raves adjacent their rear ends, knees disposed between the bights of the strut members and the raves and welded thereto, a cross bar extending between the front arms of the strut members and welded thereto adjacent their front ends, a bracket secured centrally to the rave cross piece to project forwardly therefrom, a segmental dished steering plate pivotally mounted on said cross bar and pivotally connected to said bracket on said rave cross piece, a curved handle bar provided with grips at its ends, said steering plate having a downwardly facing curved rim welded to said handle bar, and a deck formed of sheet metal having downwardly curved side edge portions embracing and welded to said raves and a downwardly facing curved front end welded to said rave cross piece.

2. A sled comprising raves and runners and V-shaped strut members formed integrally of a piece of tubular stock, the raves being connected at their front ends by an integral forwardly bowed rave cross piece, the rear ends of the raves being curved downwardly and merging with the rear ends of the runners, the front ends of the runners being curved upwardly and extended rearwardly into the V-shaped strut members, the bights of which are welded into the upper sides of the runners, the rear arms of the strut members being welded to the under sides of the raves adjacent their rear ends, knees disposed between the bights of the strut members and the raves and welded thereto, a cross bar extending between the front arms of the strut members and welded thereto adjacent their front ends, a bracket secured centrally to the rave cross piece to project forwardly therefrom, a steering member pivotally mounted on said cross bar and pivotally connected to said bracket on said rave cross piece, a handle bar secured to said steering member, and a deck formed of sheet metal having downwardly curved side edge portions embracing and welded to said raves and a downwardly facing curved front end welded to said rave cross piece.

3. A sled comprising raves and runners and V-shaped strut members formed integrally of a piece of tubular stock, the raves being connected at their front ends by an integral forwardly bowed rave cross piece, the rear ends of the

raves being curved downwardly and merging with the rear ends of the runners, the front ends of the runners being curved upwardly and extended rearwardly into the V-shaped strut members, the bights of which are welded to the upper sides of the runners, the rear arms of the strut members being welded to the under sides of the raves adjacent their rear ends, a cross bar extending between the front arms of the strut members and welded thereto adjacent their front ends, a bracket secured centrally to the rave cross piece to project forwardly therefrom, a segmental dished steering plate pivotally mounted on said cross bar and pivotally connected to said bracket on said rave cross piece, a curved handle bar provided with grips at its ends, said steering plate having a downwardly facing curved rim welded to said handle bar, and a deck formed of sheet metal having downwardly curved side edge portions embracing and welded to said raves and a downwardly facing curved front end welded to said rave cross piece.

4. A sled comprising raves and runners and V-shaped strut members formed integrally of a piece of tubular stock, the raves being connected at their front ends by an integral forwardly bowed rave cross piece, the rear ends of the raves being curved downwardly and merging with the rear ends of the runners, the front ends of the runners being curved upwardly and extended rearwardly into the V-shaped strut members, the bights of which are welded to the upper sides of the runners, the rear arms of the strut members being welded to the under sides of the raves adjacent their rear ends, a cross bar extending between the front arms of the strut members and welded thereto adjacent their front ends, a bracket secured centrally to the rave cross piece to project forwardly therefrom, a steering member pivotally mounted on said cross bar and pivotally connected to said bracket on said rave cross piece, a handle bar secured to said steering member, and a deck formed of sheet metal having downwardly curved side edge portions embracing and welded to said raves and a downwardly facing curved front end welded to said rave cross piece.

5. A sled comprising raves and runners and strut members formed integrally, the raves being connected at their front ends by an integral forwardly curved rave cross piece, the rear ends of the raves being turned downwardly and merging with the rear ends of the runners, the front ends of the runners being turned upwardly and extended rearwardly into the downwardly bowed strut members, welded centrally to the upper sides of the runners, the rear arms of the strut members being welded to the under sides of the raves, knees disposed between the bights of the strut members and the raves and welded thereto, a cross bar extending between the front ends of the runners, a segmental dished steering plate pivotally connected to said cross bar and pivotally connected to said rave cross piece, a curved handle bar provided with grips at its ends, said steering plate having a downwardly facing curved rim welded to said handle bar, and a deck secured to said raves.

6. A sled comprising raves and runners and strut members formed integrally, the raves being connected at their front ends by an integral forwardly curved rave cross piece, the rear ends of the raves being turned downwardly and merging with the rear ends of the runners, the front ends of the runners being turned upwardly and

extended rearwardly into the downwardly bowed strut members welded centrally of the runners to the upper sides of the runners, the rear arms of the strut members being welded to the under sides of the raves, knees disposed between the bights of the strut members and the raves and welded thereto, a cross bar extending between the front ends of the runners, a steering member pivotally connected to said cross bar and pivotally connected to said rave cross piece, a handle bar secured to said steering member, and a deck secured to said raves.

7. A sled comprising raves and runners and strut members between the raves and runners, the raves being connected at their front ends by an integral rave cross piece, the rear ends of the raves being curved downwardly and merging with the rear ends of the runners, the front ends of the runners being upturned and merging with the strut members which are secured to the runners centrally thereof and to the raves adjacent their rear ends, knees disposed between the strut members at their point of attachment to the runners and to the raves and secured thereto, a cross bar connected to the front ends of the runners, a segmental dished steering plate pivotally mounted on said cross bar and pivotally connected to said rave cross piece, a curved handle bar provided with grips at its ends, said steering plate having a downwardly facing curved rim welded to said handle bar, and a deck formed of sheet metal having downwardly curved side edge portions engaging and fixedly secured to said raves and a downwardly facing curved front end fixedly secured to said rave cross piece.

8. A sled comprising raves and runners and strut members between the raves and runners, the raves being connected at their front ends by an integral rave cross piece, the rear ends of the raves being curved downwardly and merging with the rear ends of the runners, the front ends of the runners being upturned and merging with the strut members which are secured to the runners centrally thereof and to the raves adjacent their rear ends, a cross bar connected to the front ends of the runners, a segmental dished steering plate pivotally mounted on said cross bar and pivotally connected to said rave cross piece, a curved handle bar provided with grips at its ends, said steering plate having a downwardly facing

curved rim welded to said handle bar, and a deck formed of sheet metal having downwardly curved side edge portions engaging and fixedly secured to said raves and a downwardly facing curved front end fixedly secured to said rave cross piece.

5 9. A sled comprising raves and runners and strut members between the raves and runners, the raves being connected at their front ends by an integral rave cross piece, the rear ends of the raves being curved downwardly and merging with the rear ends of the runners, the front ends of the runners being upturned and merging with the strut members which are secured to the runners centrally thereof and to the raves adjacent their rear ends, knees disposed between the strut members at their point of attachment to the runners and to the raves and secured thereto, a cross bar connected to the front ends of the runners, a steering member pivotally mounted on said cross bar and pivotally connected to said rave cross piece, a handle bar, and a deck fixedly connected to said raves.

10 15. A sled comprising raves and runners and strut members between the raves and runners, the raves being connected at their front ends by an integral rave cross piece, the rear ends of the raves being curved downwardly and merging with the rear ends of the runners, the front ends of the runners being upturned and merging with the strut members which are secured to the runners centrally thereof and to the raves adjacent their rear ends, a cross bar connected to the front ends of the runners, a steering member pivotally mounted on said cross bar and pivotally connected to said rave cross piece, a handle bar, and a deck fixedly connected to said raves.

20 25. A sled comprising raves and runners and strut members between the raves and runners, the raves being connected at their front ends by an integral rave cross piece, the rear ends of the raves being curved downwardly and merging with the rear ends of the runners, the front ends of the runners being upturned and merging with the strut members which are secured to the runners centrally thereof and to the raves adjacent their rear ends, a cross bar connected to the front ends of the runners, a steering member pivotally mounted on said cross bar and pivotally connected to said rave cross piece, a handle bar, and a deck fixedly connected to said raves.

30 35. A sled comprising raves and runners and strut members between the raves and runners, the raves being connected at their front ends by an integral rave cross piece, the rear ends of the raves being curved downwardly and merging with the rear ends of the runners, the front ends of the runners being upturned and merging with the strut members which are secured to the runners centrally thereof and to the raves adjacent their rear ends, a cross bar connected to the front ends of the runners, a steering member pivotally mounted on said cross bar and pivotally connected to said rave cross piece, a handle bar, and a deck fixedly connected to said raves.
